LINT COTTON CLEANER

Arvel L. Vandergriff and Donald W. Van Doorn, Columbus, Ga., assignors to Lummus Cotton Gin Company, a corporation of Georgia

Application May 13, 1957, Serial No. 658,869

7 Claims. (Cl. 19—67)

This invention relates to lint cotton cleaners of that class wherein a bat of lint cotton is fed onto a combing cylinder where it is combed to such thinness as to loosen the trash and foreign matter clinging to the lint whereby the trash is separated from the lint and thrown off from the combing cylinder by centrifugal force.

An object of our invention is to provide a lint cotton cleaner of the character designated in which the loss of fiber with the trash is greatly lessened.

A more specific object of our invention is to provide, means to eliminate the formation of fringes or tufts of lint cotton which form along the lower edge of the feed plate in lint cotton cleaners of the type to which this invention relates.

In the operation of lint cotton cleaners wherein a bat of lint-cotton is combed or drawn out over the edge of a feed plate by a combing cylinder into a thin layer from which trash and other foreign material is separated out and the cleaned lint carried away in a lint duct by a current of air, difficulties have been encountered due to the formation of fringes or tufts of lint along the lower edge of the feed plate. Foreign matter combed out of the lint fibers tends to reaccumulate in these fringes or tufts, thus lowering the efficiency of the machines. Also, as these tufts accumulate and are pulled away by action of the combing cylinder, a stronger current of air is necessary to carry them into the lint duct. This stronger current of air forces more trash and foreign matter into the lint duct, further reducing the efficiency of the machine.

We have discovered that the formation of the above described fringes and tufts may be eliminated by the provision of a deflector bar which extends across the combing cylinder beneath the feed plate and which has a thin edge extending upwardly between the lower end surface of the feed plate and the combing cylinder and which covers the surface of the combing cylinder over the width of several teeth. We have also provided improved means for the admission of air into the lint duct whereby the separation of foreign material from the lint is not impaired and a minimum volume for air for conveying the lint is required.

Apparatus embodying features of our invention is shown in the accompanying drawings, forming a part of this application, in which;

Fig. 1 is a front elevation with parts broken away;

Fig. 2 is a transverse sectional view;

Fig. 3 is a partial sectional plan view drawn to a larger scale;

Fig. 4 is a partial transverse sectional view drawn to a larger scale;

Fig. 5 is a detail sectional view showing means for adjusting the partition at the entrance to the lint duct; and,

Fig. 6 is a sectional plan view of the detail shown in Fig. 5.

Referring to the drawings, we show a casing 10 in which is mounted a combing cylinder 11. In the example

2

shown, the combing cylinder is in the form of an imperforate cylinder with spirally wound rows of saw teeth 13 mounted thereon. However, various forms of combing cylinders are known in the art and it will be apparent that other forms than the one here shown may be employed. The teeth 13 on the combing cylinder are generally radially disposed, as shown in Fig. 4, for a reason to be later described. A removable cover 14 gives access to the combing cylinder.

10 Mounted in front of the combing cylinder 11 is a feed plate assembly 16 which, in the example shown, is comprised of a multiplicity of intermediate members 16a and outer members 16b mounted in side by side relation so as to present a substantially continuous surface as shown in Fig. 3 of the drawing. The members 16a are pivoted intermediate their ends over a bar 17 which extends from end to end of the casing, it being mounted in brackets 18 (only one of which is shown) in the ends of the casing. The forward ends 19 of the feed plate members 16a are connected to springs 21 the lower ends of which are connected to anchors 22 mounted on a channel-like bracket 23 secured at its ends to the casing. Downward movement of the forward ends 19 is limited by means of adjusting bolts 24 which carry abutments 26 on their lower ends adapted to bear against the brackets 23.

15 Mounted in the casing over the feed plate assembly just described is a lint slide 27. Mounted on the outermost feed plate members 16b (only one being shown) is a guide plate 29 which directs a bat of lint being fed into the machine under a fluted roller 31 mounted directly over the feed plate assembly 16. The setting of the springs 21 determines the relation of the feed plate assembly to the feed roller 31 while permitting any one of the feed plate members to move downwardly responsive to a wad of cotton or a hard object coming between the feed roller and that feed plate member. Lint cotton to be cleaned is fed into the forward upper part of the casing 10 by means of a pair of feed rollers 32.

20 As will be seen from a consideration of Figs. 2 and 4, the ends of the feed plate members 16a and 16b adjacent the combing cylinder 11 are of considerable relative thickness. Each is provided with an upwardly dished upper surface 33 near its terminus adjacent the combing cylinder 11. The end of each member adjacent the combing cylinder is curved oppositely to the curvature of the combing cylinder 11 whereby the end surface approaches and then recedes away from the teeth 13 of the combing cylinder, as shown at 34. This surface is next curved at a sharper radius as shown at 36 to merge with the underside of the feed plate member.

25 Mounted below the feed plate assembly and extending axially across the casing 10 adjacent the combing cylinder 11 is a deflector member 37. The deflector member 37 is provided with relatively thin upper and lower edges 38 and 39 and is curved about the surface of the combing cylinder 11, closely adjacent thereto, for the distance of approximately 15°, or, as shown. The deflector member 37 has a body portion 41 curved in cross section underneath the feed plate assembly and is secured against angular movement by means of cap screws 42 and 43 extending through the ends of the casing into the deflector member.

30 In operation, the combing cylinder 11 rotates counterclockwise, as viewed in Figs. 2 and 4, and in its rotation creates a relatively mild current of air. In order to prevent air from being drawn in around the ends of the combing cylinder below the feed plate assembly and baffle member 37, we mount plates 44 in the ends of the casing, the plates having curved flanges 45 thereon which extend for a short distance over the ends of the cylinder 11 and parallel thereto.

35 The space in the casing below the feed plate assembly forms a trash receiving chamber 46, access being had

thereto by means of a removable door 47. The rear of the trash chamber 46 is formed by a generally upright partition member 48 which is fixedly mounted on a bar 49 which extends from end to end of the casing. At the top of the partition member 48 is mounted a curved plate 51 spaced from the combing cylinder 11 to form a passage 52 for the lint being carried around by the combining cylinder. The bar 49 extends through the casing as shown in Fig. 6, and has an arm 53 mounted thereon and carrying on its outer end a spring pressed latch 54a which is adapted to engage selectively in a plurality of recesses 54 to adjust the position of the plate 51 angularly with respect to the combing cylinder.

At the rear of the casing 10 there is connected a lint duct 55 having an upper wall 56 which joins to a wall 57 in the casing 10 at the rear of the combing cylinder 11. The lower wall 58 of the lint duct 55 extends downwardly and forwardly to a point below the rear end of the plate 51 and is provided with an adjustable inlet 59 for the admission of air, it being understood that sub-atmospheric pressure is maintained within the lint duct 55. The quantity of air admitted through the inlet 59 may be regulated by means of a slide 61. The upper wall 57 of the lint duct extends inwardly to a point near the combing cylinder 11 and thence generally parallel to the combining cylinder to join the combing cylinder cover 14.

In operation, the cotton is fed downwardly into the casing by the feed rollers 32 onto the lint slide 27 and thence downwardly under the fluted feed roller 31 which rotates in a counterclockwise direction, as viewed in the drawings, to deliver the cotton over the nose of the feed plate assembly 16. Should a large wad of cotton or a foreign object be in the lint the springs 21 permit the feed plate members to move downwardly. This downward movement is limited by the deflector member 37. The cotton passing the feed plate assembly is there engaged by the combing cylinder 11 and as the bat passes over the nose of the feed plate the fibers are aligned and foreign matter is loosened from the tangled fibers. The fibers are carried by the combing cylinder past the deflector member 37 and the teeth 13 of the combing cylinder being substantially radial, as they pass the lower edge 39 of the deflector member, trash and other foreign matter is released and thrown off by centrifugal force. Rotation of the combing cylinder 11 creates a gentle current of air which moves downwardly close to the surface of the cylinder and over the plate 51 through the passage 52. The action of the air current causes the fibers to be held in close proximity to the surface of the combing cylinder by the air current. The fibers pass through the passage 52 into the lint duct 55 and are thrown off the combing cylinder 11 by centrifugal force aided by air entering the lint duct through the passage 59.

The air inlet slot 59 being located behind the trash chamber wall 48, the conveying air does not interfere with the discharge of foreign material into the trash chamber.

The provision of the deflector member 37, with its thin upper edge projecting into the space between the end of the feed plate assembly and the surface of the combing cylinder eliminates the space in which fringes have normally formed in prior art apparatus. The lower edge of the deflector member 37 is also made thin and the bottom surface is so designed as to allow the air current to approach the moving surface of the combing cylinder 11 without turbulence. Since there is no turbulence at the bottom edge of the deflector member this cause of fringe formation is eliminated. Also, the distance from the nose of the feed plate to the bottom of the deflector plate is sufficiently great for any streamers of lint to be broken up before reaching the bottom edge of the feed plate and this cause of fringe formation is eliminated.

With the fringe eliminated, the lint fibers are uniformly distributed over the surface of the combing cylinder

and it is unnecessary for a strong current of air to enter the lint duct to prevent the loss of lint with the foreign matter. This makes it possible to allow the conveying air to enter through the air inlet slot 59 at the rear of the partition 48 and only the air generated by the moving surface of the combing cylinder 11 enters the open end of the lint duct.

From the foregoing it will be apparent that we have devised an improved lint cleaning apparatus which is simple of design and reliable in operation.

While we have shown our invention in but one form, it will be obvious to those skilled in the art that it is not so limited, but is susceptible of various other changes and modifications without departing from the spirit thereof, and we desire, therefore, that only such limitations shall be placed thereupon as are specifically set forth in the appended claims.

What we claim is:

1. In a lint cotton cleaner, a combing cylinder, a casing for the combing cylinder having an inlet for cotton to a cleaned near the upper front thereof, an outlet duct for cleaned cotton at the rear having a lower wall extending downwardly beneath the combing cylinder, a generally upright partition member extending across the casing beneath the combing cylinder adjacent the inner end of the duct forming the rear wall of a trash chamber, a feed roller adjacent the forward downgoing side of the combing cylinder, a feed plate assembly cooperating with the feed roller and having an upwardly curved upper surface adjacent the combing cylinder, the surface facing the combing cylinder being curved downwardly toward and then away from the combing cylinder for the distance of several teeth on the said cylinder, a deflector member mounted beneath the feed plate and extending across the casing in front of the said cylinder, one edge thereof of extending upwardly between the rear end of the feed plate and the said cylinder, said deflector member having a curved surface extending around the said cylinder relatively close thereto for a considerable distance, and means to permit a current of air to enter into the lint duct at the rear of the partition.
2. Apparatus as defined in claim 1 in which the feed plate is comprised of a plurality of sections mounted side by side to form a substantially continuous surface, and means resiliently urging the upper curved surfaces of the feed plate sections toward the feed roller.
3. Apparatus as defined in claim 1 in which the combing cylinder is provided with teeth which are substantially radial thereto whereby the lint and trash are drawn thereby past the feed plate and deflector member and the trash is thrown off tangentially downward from the combing cylinder, into the trash chamber, and the lint is thrown off by centrifugal force into the lint duct and is carried away by the air current.
4. In a lint cotton cleaner in which a bat of lint cotton is combed by a combing cylinder into a thin layer which loosens the trash therein and the trash is then thrown off the combing cylinder and separated from the lint by centrifugal force and the lint enters a lint duct at the rear of the combing cylinder and is carried away by a current of air, the improvement which comprises a spring pressed feed plate assembly having a dished upper surface terminating adjacent the downgoing side of the combing cylinder and having its surface facing the combing cylinder curved toward and then away from the combing cylinder, a feed roller cooperating with the upper surface of the feed plate, and a deflector member mounted directly beneath the feed plate and extending downwardly closely adjacent the said cylinder for a distance of approximately 15°, the upper edge of said deflector member extending upwardly between the lower portion of the feed plate assembly and the combing cylinder.
5. In a lint cotton cleaner in which a bat of lint cotton is combed by a combing cylinder into a thin layer

which loosens the trash therein and the trash is then thrown off the combing cylinder and separated from the lint by centrifugal force and the lint enters a lint duct and is carried away by a current of air, the improvement which comprises a casing in which the combing cylinder is mounted, a lint duct joined to the casing at the rear, a lower wall of the lint duct extending downwardly and terminating directly below the combing cylinder, an inlet for cotton at the upper front of the casing, a partition member mounted below the combing cylinder in spaced relation thereto adjacent the terminus of the lower wall of the lint duct and extending generally downward to the bottom of the casing to form the rear wall of a trash chamber in the lower front of the casing, a plate joined to the upper edge of the partition member and extending across the casing in spaced relation to the combing cylinder to form an entrance into the lint duct, means to permit an air stream to enter into the lint duct at the rear of the partition member, and means to adjust the partition member angularly relative to the said cylinder.

6. In a lint cotton cleaner, a casing having an inlet for cotton to be cleaned in the upper front portion thereof, a combing cylinder mounted in the casing, a dished feed plate assembly mounted closely adjacent the downgoing side of the combing cylinder with its end facing the combing cylinder curved toward and then away from the combing cylinder, a feed roller cooperating with the upper surface of the feed plate assembly, a deflector member having relatively thin upper and lower edges mounted beneath the feed plate in closely spaced relation to the combing cylinder and extending axially thereof and having its upper edge extending upwardly between the combing cylinder and the end of the feed plate assembly facing the combing cylinder, a lint duct at the rear of the combing cylinder having one wall terminating under the combing cylinder, a partition member mounted adjacent the entrance to the lint duct in spaced

5 relation to the combing cylinder and extending downwardly to define a trash chamber in the lower front of the casing, and means to permit a current of air to enter into the lint duct at the rear of the partition member.

7. In a lint cotton cleaner, a casing having an inlet for cotton to be cleaned in the upper front portion thereof, a combing cylinder mounted in the casing, a dished feed plate assembly mounted closely adjacent the downgoing side of the combing cylinder with its end facing the combing cylinder curved toward and then away from the combing cylinder, a feed roller cooperating with the upper surface of the feed plate, a deflector plate having relatively thin upper and lower edges mounted beneath the feed plate assembly and having its upper edge extending upwardly between the combing cylinder and the end of the feed plate facing the combing cylinder and extending axially thereof, a lint duct at the rear of the combing cylinder having one wall terminating under the combing cylinder, a partition member mounted adjacent the entrance to the lint duct in spaced relation to the combing cylinder and extending downwardly to define a trash chamber in the lower front of the casing, a plate joined to the top of the partition member and extending across the casing rearwardly toward the entrance to the lint duct, means to adjust the partition member angularly relative to the combing cylinder, and means to permit a current of air to enter into the casing at the rear of the partition into the lint duct.
